UNITED STATES PATENT OFFICE

FREDERIC B. SHAW, OF BOSTON, MASSACHUSETTS.

LUBRICATOR.

SPECIFICATION forming part of Letters Patent No. 248,356, dated October 18, 1881.

Application filed October 11, 1880. (No model.)

To all whom it may concern:

Be it known that I, FREDERIC B. SHAW, of Boston, in the county of Suffolk and State of Massachusetts, have invented a new and useful Improvement in Lubricators, of which the following is a specification.

The object of my invention is to produce an oil-cup or lubricator for journals and bearings, whether movable or stationary, which shall be simple in construction and free from all liability to injury by the admission of dust or other deleterious substances.

The invention consists in the combination, with the cup that holds the lubricating material, of a piston, which is fitted in the said cup so as to be oil-tight, and is connected to a rod which is attached to the upper part of a cap that screws down over the cup, and is turned with the cap, so that by turning the cap in one direction the lubricating substance will be forced downward and out through a passage in the nipple at the lower end of the cup, to supply the lubricating substance or compound to the journals or shafts to which the cup is attached, as desired.

Referring to the drawings, Figure 1 is an elevation of my invention, and Fig. 2 a vertical section of the same.

The lubricator may be made of any suitable metal, brass or composition being preferred.

A is a cup, having at its lower end a nipple, G, which may be provided with a screw-thread for attachment to a bearing or journal, and has a central opening for the passage of the lubricating substance. On the upper outer end of the cup A is a screw-thread, a.

B is a cap or cover, provided with a screw-thread on its inner surface, and extending the whole length of the same, as shown in Fig. 2.

Within the cup A is snugly fitted, so as to

render it oil-tight, a piston, C, attached to a rod or bar, D, the upper part of which, at E, is made square and fits in a corresponding hole in the top of the cap, and is secured in the same by a nut, F, screwed upon the upper end of the rod D, so that the piston can be readily removed and replaced when necessary or desirable for cleaning, &c.

The piston C may be provided with a packing in a groove on its perimeter, if desirable. By turning the cap B in one direction the piston C will be forced down and the lubricating substance be expelled, as required.

It will be seen that no part of the inside of the cup, the piston-rod, or the lubricating substance is liable to exposure to or the action of dust, water, or vapor when in use, whether at sea or on land.

I am aware of the Patent No. 71,101, granted November 19, 1867, in which is shown a solid plunger made part of the cover of the lubricator, and having a cup passing up in a narrow space between the two. This I do not claim; but

What I do claim as my invention is—

A lubricator composed of the cap B, having an internal screw-thread, and provided with a detachable rod, D, carrying a piston, C, and a cup, A, having an internal smooth surface and an external screw-thread at its upper end, and provided with a screw-nipple, G, and a discharge-passage, all as shown and set forth.

In testimony whereof I have signed my name to this specification in the presence of two subscribing witnesses.

FRED. B. SHAW.
